UNITED STATES PATENT OFFICE

ARTHUR G. BORDEN, OF WASHINGTON, DISTRICT OF COLUMBIA, ASSIGNOR TO THE BORDEN METHOD, INC., OF WASHINGTON, DISTRICT OF COLUMBIA, A CORPORATION OF DELAWARE

PERMANENT-HAIR-WAVING APPLIANCE

Application filed July 5, 1927. Serial No. 203,328.

My invention relates to improvements in the appliances or method used in preparing the hair of a person for permanently waving, and the object of my improvements are, 5 first to protect the patron from excessive heat or burns; second to simplify the operation, allowing the operator to prepare the hair in the shortest time possible and with the utmost ease; third, to eliminate tying the 10 hair to any part of the appliance either at the roots of the hair or at the ends; fourth to wrap the hair more smoothly and tighter on the waving rod by a simplified mechanical winder.

15 I attain these objects by a mechanism illustrated in the accompanying drawings, in which:—

Figure 1 is an elevation of the curling rod showing the improved base and winder for 20 back wrapping the hair preparatory to a steaming operation;

Fig. 2 is a longitudinal cross-sectional view taken through the heater showing the curling rod inserted therein for a steaming operation;

Fig. 3 is a lateral cross-sectional view through the assembled heater taken on line 3—3 of Fig. 2;

Fig. 4 is a lateral cross-sectional view on 30 line 4—4 of Fig. 2 showing the absorbent gasket members which are disposed at the base of the heater for preventing leakage of condensate upon the patron;

Fig. 5 is a lateral view taken on line 5—5 35 of Fig. 2 showing the metal clamping discs which secure the hair in a position in which it may be wrapped on the curling rod;

Fig. 6 is a lateral view taken on line 6—6 40 of Fig. 2 showing the construction of the base by which the scalp is protected against excessive heat;

Fig. 7 is a side elevation of the protecting pad which is provided at the entrance of the 45 heater;

Fig. 8 is a view showing the several parts of the curling rod and winder preparatory to assembly as a unit;

Fig. 9 is a side elevation of the clamping 50 device employed to maintain the hair in

wrapped formation in a central position with- in the heater;

Fig. 10 is an end view of the clamping device shown in Fig. 9;

Fig. 11 is a plan view of the upper plate 55 used for securing the hair in the heater;

Fig. 12 is a view of the lower plate used for the purpose of securing the hair in the heater;

Fig. 13 is a side elevational view partially 60 in cross-section showing the heat resisting winder employed in the apparatus of my invention;

Fig. 14 is a plan view of the heat resisting winder;

Fig. 15 is a cross-sectional view taken through the heater showing a modified form of clamping means for securing the hair in wrapped formation within the heater;

Fig. 16 is an elevational view of a modified 70 form of clamping device for the hair curling rod;

Fig. 17 is a side view of the clamping de- vice shown in Fig. 16; and

Fig. 18 is a plan view of the top of the 75 clamping device illustrated in Figs. 16 and 17.

Referring more particularly to the drawings reference character 1 designates a center rod member upon which the hair design- 80 ated at 2 may be wrapped. The rod mem- ber is interiorly screw threaded at the end

thereof as represented at 3 to receive the screw 4 which is secured to the disc 5. The disc 5 is provided with out-struck projec- 85 tions 6 through which rivet members 7 pass for securing the plate member 8 with respect thereto. The plate member 8 is provided with a felt facing pad 9 secured in a suitable manner thereto. The felt pad 9 and plate member 8 are apertured as represented at 10 90 to permit the passage of the strands of hair 2 into the heater to a position where the hair may be wrapped upon rod member 1. An in- dependent disc 11 is concentrically mounted upon rod 1 and is angularly movable with 95 respect thereto for clamping the hair in a desired position with respect to the heater. The plate 5 is provided with a projecting lug 5*, while plate 11 is provided with a project- 100 ing lug 11* enabling the plates to be shifted

with respect to each other. The plates are each provided with arcuate slots 11^b and 5^b, respectively, through which the hair may be passed and clamped during the waving process. The plate member 5 has an upstruck lug 5^c, while the upper plate 11 has a downstruck lug 11^c which cooperate to prevent any shearing effect with respect to the hair. In this manner a large flat surface is presented to the strands of hair at opposite ends of the slots when the plates are respectively moved, as shown more clearly in Fig. 5. The vertically extending rod 1 is provided with a head portion 12 which may be gripped by a suitable spring clamping device, represented more clearly in Fig. 15 for securing the hair waver in position within the heater. The spring gripping device is shown as comprising a spring snap structure 14 cooperating with the groove on the head 12 of rod member 1. A cap 15 is provided fitted within the end of heater 16 and retained in spring pressed position therein by means of spring 17. This spring tends to constantly urge the rod member 1 in a vertical direction, thereby drawing that end of the rod upon which hair is wrapped to a position within the heater.

It will be observed that a positive air space is provided between the upper surface of the plate member 8 and the lower surface of the disc 5. Circulation of air is permitted through this gap thereby reducing the conduction of heat to the head of the patron under treatment. In order to hermetically close the heater and prevent condensation from dripping from the heater upon the head of a patron under treatment, I provide a plurality of absorbent pad members 18. The structure is laminated and built up from a plurality of independent fibrous washers tending to absorb moisture which may be developed within the heater.

As shown more clearly in Fig. 4 each of the laminations consists of flat sheets having diametrically extending cuts 19 adjacent the center thereof thus providing upstanding ears 20 as represented in Fig. 2 for the protection of the patron from leakage of condensation. The heater 16 may be of double walled construction having the heating element 21 embedded therein, and a flexible electrical connection extending therefrom as represented at 22. On the rod member 1 I provide a mechanical winder and fastener for the hair 23 constituted by a cylindrical member. The mechanical winder is formed of heat-resisting material, such as fiber or bakelite having no metal to absorb heat and no sharp edges to cut or break the hair. The winder has a cylinder portion and a fastener portion with a prong 24 extending laterally therefrom, providing means for catching the hair by a simple twist of the winder. The ends of the hair are firmly held in a V-shaped slot 25 which extends longitudinally of the

winder 23. The hair may be tightly secured in this slot by passing the strands through the opening provided between the winder proper and the laterally extending prong 24. It will be seen that the winder is longitudinally slideable along the rod. The strands of hair may be passed through the aperture 10 in the pad 9, the corresponding aperture in plate 8 and the aperture 5^b and 11^b in plates 5 and 11 into the heater chamber 26. In applying the hair to the winder the heater 16 is normally removed from a position surrounding rod 1 and winder 23 occupies a position adjacent the lower extremity of rod 1 by which the hair may be locked into the winder. By applying pressure to the winder and revolving the same by a twist of the fingers the hair may be tightly wound upon rod 1 and built up in a spiral thereon holding all of the strands uniform and eliminating time heretofore required in hand winding of hair. After the hair is wound upon the rod and the winder occupies a position adjacent the upper extremity of the rod as represented in Figs. 2 and 15, a strip of flannel designated at 27 saturated with a suitable softening solution required in all permanent waving is wrapped around the hair while wound upon rod 1. The natural dampness of the flannel strip 27 enables the strip to be retained in position. The heater chamber 16 is then inserted over the hair in its wrapped form assuming the position illustrated in Fig. 15.

In Fig. 2 I have illustrated a method of centering the rod 1 with hair wound thereon within the heater chamber 26 and at the same time providing means for retaining the flannel cloth 27 in position and holding the assembled discs 18 tightly against the lower extremity of the heater 16 constituting a hermetic closure for the heater. This is accomplished by means of the yoke member 28 represented more clearly in Figs. 9 and 10 as comprising a pair of spring arms normally bowed outwardly and embracing the interior walls of the heater chamber 26. The yoke is apertured at the extremity 29 to permit the rod 1 to be passed therethrough.

In Figs. 16 and 17 I have shown a modified form of yoke having a side opening member 30 at the top thereof constituted by a pair of spring jaws which may be slipped sideways over the rod 1 for centering the rod within the heater chamber and retaining the wrapping 27 in position with respect to the rod 1.

By applying downward pressure on the winder 23 the ends of the hair are back-wrapped thus giving a more decided spring or curl to the hair.

The appliance of my invention has been used with extremely successful results and produces a permanent wave to the hair indistinguishable from naturally curly hair.

The appliance is convenient to operate and

thorough protection to the patron is assured. The structure of the appliance is extremely simple to operate and the parts may be manufactured inexpensively upon a quantity production scale.

5 While I have described certain preferred embodiments of my invention, I desire that it be understood that modifications may be made and that no limitations upon my invention are intended other than are imposed by the scope of the appended claims.

10 What I claim as new and desire to secure by Letters Patent of the United States is as follows:

15 1. In a hair waving appliance, a heater member, a tubular casing enclosing said heater member, a rod member extending centrally through said casing, a base connected to said rod member for closing the end of said casing, said rod member forming a central axis about which hair may be curled, and clamping means secured over the hair in curled formation for maintaining the rod member centrally within said casing and 20 for providing an annular air gap between the interior walls of said casing and the hair curled on said rod throughout the path of movement of said rod with respect to said casing.

25 30 2. In a hair waving appliance a heating chamber, a central rod member for receiving hair in wrapped formation, a base secured to the end of said rod member for closing the end of said chamber when said rod member with hair wrapped thereon is moved into said chamber, and spring means surrounding said rod member and frictionally engaging the inner walls of said chamber for maintaining the hair in spaced relation to the interior walls of said heating chamber throughout the path of movement of said rod with respect to said chamber.

35 40 45 50 55 3. In a hair waving appliance, a tubular shaped heating chamber, a central rod member for receiving hair in wrapped formation thereon, said rod having a base adapted to close the end of said chamber when said rod member is moved into the chamber, a yoke member of spring material positioned over said rod member and frictionally engaging the inner walls of said chamber for maintaining the hair in spaced relation to the interior walls of said chamber throughout the path of movement of said rod with respect to said chamber.

60 65 4. In a hair waving appliance, a tubular shaped heating chamber, a curling rod projectable centrally within said chamber, a base secured to said curling rod for closing the end of said chamber when said rod is moved to a position interiorly of the chamber, said base being apertured for the passage of hair therethrough, means for wrapping the hair on said rod, and clamping means embracing the hair on said rod, said clamping means

being centered with respect to said rod and having portions thereof frictionally engaging diametrically opposite parts of the inner wall of said chamber for maintaining the hair within said chamber out of contact with the interior walls thereof during a steaming operation.

5 10 15 20 25 30 35 40 45 50 55 60 65 70 75 80 85 90 95 100 105 110 115 120 125 130 7. In a hair waving appliance, a tubular heating chamber, a rod member projectable centrally into said chamber, a base connected to said rod member for normally closing the end of said chamber, said base being apertured for the passage of hair therethrough to a position where the hair may be wrapped upon said rod, and means disposed between said base and the end of said chamber for absorbing moisture from said chamber and preventing leakage thereof below said base.

6. In a hair waving appliance a tubular heating chamber, a rod member projectable centrally therein, a base carried by said rod member for normally closing the end of said chamber when said rod is moved to a position within the chamber, said base comprising a disc extending substantially normal to said rod with a plurality of discs extending parallel thereto, moisture absorbing pads carried by said discs.

7. In a hair waving appliance, a tubular shaped heater chamber, a hair curling rod insertable centrally within said chamber, a base carried by said rod for closing the end of said chamber when the rod is projected to a position interiorly of said chamber, said base being provided with a plurality of parallel extending discs, one of said discs providing a support for a plurality of moisture absorbing means adapted to substantially close the end of said heater chamber and prevent leakage of moisture therefrom, and the other of said discs providing a support for a heat-resisting pad.

8. In a hair waving appliance, a tubular shaped heater chamber, a hair curling rod insertable centrally within said chamber, a base carried by said rod for closing the end of said chamber when the rod is projected to a position interiorly of said chamber, said base being provided with a plurality of parallel extending discs, one of said discs providing a support for a plurality of moisture absorbing means, and the other of said discs providing a support for a heat-resisting pad, said discs being spaced one from the other for establishing a circulatory air path therebetween for substantially preventing conduction of heat from said chamber to said last mentioned disc.

9. In a hair waving appliance a tubular shaped heater, a hair curling rod projectable to a position within said heater, a base member extending normal to said hair curling rod for closing the end of said chamber when said rod is moved to a position interiorly of said chamber, said base member including a

pair of angularly movable discs apertured for the passage of hair therethrough to a position where the hair may be wrapped upon said rod, moisture absorbing means disposed between one of said discs and the end of said chamber and a facing pad supported by the other of said discs, the disc supporting said moisture absorbing means being positively spaced from the disc supporting said facing pad for establishing a circulatory air path therebetween and substantially preventing heat conduction from said chamber to said facing pad.

10. In a hair waving appliance a heater chamber, a hair curling rod insertable centrally within said chamber, means carried by the end of said rod for closing the end of said chamber, said means being constituted by a plurality of plates spaced one from the other 20 with a gap for the free passage of air therebetween, one of said plates having a facing pad thereon, each of said plates being apertured to permit the passage of hair into said chamber for engagement by said hair curling 25 rod whereby transfer of heat from said chamber to said facing pad is substantially prevented by dissipation of said heat between said plates.

11. In a hair waving appliance a heater chamber, a hair curling rod insertable centrally within said heater chamber, a base carried by said rod for closing the end of said heater chamber while permitting the entrance of hair into said heater chamber for 35 engagement by said curling rod, said base being constituted by a plurality of plates separated one from the other for the free passage of air therebetween, moisture absorbent pads carried by said base for closing the end 40 of said heater chamber and a facing pad carried by one of said plates whereby conduction of heat from said chamber to said facing pad is substantially reduced.

12. In a hair waving appliance a heater 45 chamber, a rod insertable into said heater chamber, a base carried by said rod and normally closing said heater chamber, said base being constituted by a plurality of plates spaced one from the other for the passage 50 of air freely therebetween for facilitating the radiation of heat from said plates, one of said plates carrying a heat resisting pad for protecting the patron from contact with said heater chamber and a multiplicity of 55 moisture absorbent pads in stacked relation between said base and the end of said chamber for preventing seepage of condensate from said chamber upon the patron.

In testimony whereof I affix my signature.
30 ARTHUR G. BORDEN.
